(57) **CLAIM**

The ornamental design for a capsule chamber, as shown and described.

DESCRIPTION

FIG. 1 is a perspective view of a capsule chamber showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The drawings include surface shading that represents contour and not surface ornamentation.

The broken lines in the drawing depict portions of the capsule chamber that form no part of the claimed design.
